RALPH D. MATTESON, OF BOISE, IDAHO

AIR CLEANING AND MOISTENING DEVICE

Application filed November 18, 1930. Serial No. 496,476.

The present invention comprehends the provision of a motor attachment in the nature of an air cleaning and moistening device, whereby the air is introduced into the carbureter of the motor in a clean and moistened condition, and thereby increases the efficiency of the motor.

One of the chief characteristics of the present invention resides in the construction of a device for this purpose, through which the air is caused to pursue an irregular course before entering the carbureter, so that air is thoroughly cleaned, and properly moistened to the desired extent before leaving the device.

Another object of the invention resides in the provision of a device of the character above-mentioned, constructed to be easily associated with the carbureter, and supplied with water from the pump of the motor in the necessary or desired amount to moisten the air passing through the device.

The invention also contemplates the provision of a device of this character, wherein the component parts can be quickly and easily assembled or disassembled, and the air moistening and cleaning elements replaced from time to time as the occasion may require.

The nature and advantages of the invention will be better understood when the following detailed description is read in connection with the accompanying drawings, the invention residing in the construction, combination and arrangement of parts as claimed.

In the drawings forming part of this application like numerals of reference indicate similar parts in the several views and where-
40 in:

Figure 1 is a side elevation of a motor showing the application of the invention.

Figure 2 is a longitudinal sectional view through the attachment.

Figure 3 is a sectional view on line 3-3 of Figure 2.

Figure 4 is a sectional view on line 4-4 of Figure 2.

Figure 5 is a perspective view of the closure for one end of the device.

Referring to the drawings in detail, 10 indicates generally a motor of any well known construction, the carbureter for which is shown at 11 and the water pump at 12.

The device forming the subject matter of the present invention comprises a casing adapted to be coupled with the carbureter 11, and through which casing the air passes in entering the carbureter, and dealt with in a manner to thoroughly clean the air as well as moisten the same prior to its introduction into the carbureter. In the specific embodiment of the invention herein illustrated, the device embodies spaced inner and outer casings 13 and 14 respectively, and while these casings are substantially of the same length, it will be noted upon inspection of Figure 2 that the inner casing 13 is spaced a slight distance from the closed end wall 15 of the outer casing, the opposite end of this casing being open with the inner casing 13 projecting a slight distance beyond this last-mentioned end of the outer casing 14. The closed end wall 15 of the outer casing is curved as illustrated for a purpose to be presently described, 75 while the outer end of the inner casing 13 is provided with a suitable cap or closure 16. Projecting centrally from the closed end of the outer casing 14 is a hollow sleeve-like coupling 17 for associating the device with the carbureter 11 and which coupling of course constitutes the outlet for the device. The coupling sleeve 17 projects an appreciable distance within both the inner and outer casings, and supported by this sleeve 17 is a liquid absorbent element which is located centrally within the inner casing 13.

While this element may vary in construction and design, it preferably consists of a cylindrical member 18 of suitable absorbent material which is reinforced on opposite sides by foraminated material, such as fine mesh wire 19. The element is also reinforced at its opposite end by substantially U-shaped metallic rings 20 which embrace the component parts of the element as illustrated. As above stated this liquid absorbent element is supported by the inner end of the coupling sleeve 17, and is substantially co-extensive in length with the inner casing 13, although the

outer end of the element is further supported by the closure cap 16 for the inner casing 13. This cap 16 is preferably provided with a transverse bar 21 arranged between the angular flange 22 of the cap as clearly illustrated in Figure 5, and the bar 21 is notched at spaced points as at 23 to receive the adjacent end of the absorbent element as illustrated in Figure 2. The material struck from the bar 21 in the formation of the notches 23 is bent in opposite directions and arranged in right angular relation to the bar 21 as clearly shown in Figure 5. Manifestly when the cap 16 is located in position for use, the adjacent end 16 of the absorbent element 18 is received by the notches 23, and the angularly disposed portions 24 of the bar bear against the adjacent end of the element 18 and thereby immovably supports the element within the inner cylinder 13. Of course the absorbent element can be very easily and conveniently removed, by first removing the closure cap 16, and consequently this element can be readily replaced from time to time as the occasion may require.

25 Located within the inner casing 13 at its inner end is a disk 25 including a hub-like portion 26 supported by the coupling sleeve 17. This disk is provided with a circumferential series of slots or air passages 27 and is also 30 formed to provide angularly disposed blades 28. The purpose of this disk will be presently set forth. The space between the inner and outer casings 13 is filled with an air cleaning element, preferably in the nature of 35 steel wool which may be saturated with oil or a suitable composition for this purpose. This material is indicated at 29 and obviously can be quickly removed and replaced from time to time as the occasion may require.

40 Arising from the device is a short length of pipe 30, the upper end of which is suitably coupled with a water supply pipe 31 leading from one side of the water pump 12, so that water is conveyed through the pipe 31 into 45 the device to maintain the absorbent element 18 in a moistened condition. The water however is introduced into the device drop by drop that is to say intermittently, and in just such amount as is necessary to maintain the 50 element 18 in a properly moistened condition. For this purpose, the pipe 31 is provided with a valve 32 which can regulate the flow of water to the device, while the pipe 30 is provided with a sight tube 33 and slotted as illustrated in Figure 3 so that this tube can be 55 readily seen. Manifestly the water emitted to the device is dropped upon the absorbent element 18 to maintain the latter in a moistened condition, and any surplus water that 60 might accumulate in the inner casing 13 is conveyed therefrom through a drain pipe 34.

In practice, the device is associated with the carbureter 11, and by reason of its construction, the air enters the device from one 65 end of the outer casing 13, and through the

space between the inner and outer casings as illustrated. Consequently the air passing through the steel wool 29 is first cleaned, and as the air leaves the space just referred to, it is deflected by the curved closed wall 70 15 of the outer casing 14 into the inner casing 13. To enter this inner casing, the air must pass through the slots or passages 27 of the disk 25, which is provided with blades 28 to give the air a whirling or circular motion about the absorbent element 18, so that the air is brought into contact with this element about all sides thereof, as the air flows through the inner casing 13 in the direction of the closure cap 16. The air is finally directed into the absorbent element 18, and finally passes through the latter to be further moistened before leaving the device and entering the carbureter 11 through the coupling sleeve 17. In this manner, the air is caused to pursue an irregular course through the device before entering the carbureter 11, and is retained within the device a sufficient length of time to be thoroughly cleaned and properly moistened before entering the carbureter. As above stated, the element 18 is maintained in a moistened condition by the introduction of water from the pump 12 through the supply pipe 31, and the amount of water introduced into the device can be 80 85 regulated by means of the valve 32. The device is constructed to permit the parts to be quickly and easily assembled or disassembled as the occasion may require, and both the steel wool 29 and the absorbent element 18 to be replaced from time to time as may be necessary.

While it is believed that from the foregoing description the nature and advantages of the invention will be readily understood, I 10 desire to have it known that I do not limit myself to what is herein illustrated and described and that such changes may be resorted to when desired as fall within the scope of what is claimed.

What I claim as new is:

1. An air cleaning and moistening device for motors comprising spaced inner and outer horizontal tubular casings, said outer casing being open at one end, a closure for the adjacent end of the inner casing, whereby air enters the device through the space between said casings, a tubular liquid absorbent element located axially of and within the inner casing and through which the air passes in leaving the device, means including a water supply pipe discharging onto the top of the absorbent element for maintaining said element in a moistened condition, and an axial coupling sleeve extending from the other end of the outer casing for association with the carbureter of the motor.

2. An air cleaning and moistening device for motors comprising spaced inner and outer casings, said outer casing being open at 11

one end, a closure for the adjacent end of the inner casing, whereby air enters the device through the space between said casings, means for giving said air a whirling motion as it passes from said space into the inner casing, a liquid absorbent element arranged centrally within the inner casing and through which the air finally passes in leaving the device, means for maintaining said element in a moistened condition, and a coupling sleeve projecting from the other end of the outer casing for association with the carbureter of the motor.

3. An air cleaning and moistening device for motors comprising spaced inner and outer casings, said outer casing being open at one end, a closure for the adjacent end of the inner casing, whereby air enters the device through the space between said casings, air cleaning means arranged within said space, means for giving said air a whirling motion as it passes from said space into the inner casing, a liquid absorbent element arranged centrally of the inner casing and through which the air finally passes in leaving the device, means for maintaining said element in a moistened condition, and a coupling sleeve projecting from the other end of the outer casing for association with the carbureter of the motor.

4. An air cleaning and moistening device for motors comprising spaced inner and outer casings, said outer casing being open at one end, a closure for the adjacent end of the inner casing, whereby air enters the device through the space between said casings, an air cleaning element arranged within the space between said casings, means for giving said air a whirling motion as it passes from the said space into the inner casing, a liquid absorbent element arranged centrally of the inner casing and through which the air finally passes in leaving the device, means for intermittently introducing the water into the device to maintain said element in a moistened condition, and a coupling sleeve projecting from the other end of the outer casing for association with the carbureter of the motor.

5. An air cleaning and moistening device for motors comprising spaced inner and outer casings, said outer casing being open at one end, a closure for the adjacent end of the inner casing, whereby air enters the device through the space between said casings, an air cleaning element arranged in the space between the casings, a liquid absorbent element located centrally within the inner casing and through which the air finally passes in leaving the device, a water supply pipe leading from the pump of the motor to said inner casing for maintaining said element in a moistened condition, a valve located in said pipe for regulating the introduction of water into said inner casing, and a coupling sleeve

projecting from the other end of the outer casing for association with the carbureter of the motor.

In testimony whereof I affix my signature.
